SIDNEY WORMS, OF NEW ROCHELLE, AND JOSEF KELLNER AND FRANK HUG, OF BROOKLYN, NEW YORK, ASSIGNEES TO FRANKLIN KNITTING MILLS, INC., OF NEW YORK, N. Y., A CORPORATION OF NEW YORK

AUXILIARY NEEDLE HELPER FOR JACQUARD-KNITTING MACHINES

Application filed September 24, 1924. Serial No. 739,480.

The present invention relates to needle helpers for knitting machines, particularly for knitting machines of the class known as flat knitting machines, and aims to devise needle helpers of the general character specified above which are simple in construction, easy and economical to manufacture, and which are very well constructed and adapted to be successfully used with knitting machines of the class specified above, but especially with jacquard mechanisms adapted to be employed with such knitting machines, whereby the desired number and arrangement of needles are operated accurately and with required certainty of operation to produce the pattern predetermined by the jacquard card or its equivalent. The needle helpers of the present invention are further characterized by their durability and by their compactness of arrangement, where, as is generally the case, a plurality of such helpers are employed on a single bed, in which case the construction of the needle helpers of the present invention permits the compact but readily operative arrangement on an unusually large number of needle helpers and their corresponding needles per linear unit of length of the needle bed, thus permitting the ready, convenient and economical production of a finely and compactly knitted fabric having the desired jacquard pattern knitted into the fabric. Other objects and advantages of the present invention will appear as the following description proceeds.

In the accompanying specification we shall describe, and in the annexed drawing show, one illustrative embodiment of the devices of the present invention. It is, however, to be clearly understood that our invention is not limited to the specific embodiment thereof herein shown and described for purposes of illustration only.

Referring to the drawing, wherein the aforesaid illustrative embodiment of the present invention is illustrated:

Fig. 1 is a fragmentary side elevation, partly in cross section, showing a pair of needle helpers made in accordance with the principles of the present invention and in

position on the auxiliary jacquard or other bed;

Fig. 2 is a fragmentary end view of a series of needle helpers in a position in the corresponding slots of the auxiliary or other bed shown in Fig. 1 of the drawing;

Fig. 3 is a plan view of one of a pair of needle helpers constructed in accordance with the principles of the present invention; and

Fig. 4 is a view similar to Fig. 3 of the remaining member of a pair of needle helpers constructed in accordance with the principles of the present invention.

Referring now more particularly to the aforesaid illustrative embodiment of the present invention, and particularly to the drawing illustrating the same, 10 indicates a needle bed, in this case preferably an auxiliary needle bed adapted to be attached to a flat-knitting machine for adapting the same to be operated by suitable jacquard mechanism for the knitting of jacquard patterns into knitted fabrics. The auxiliary or other needle bed 10 is preferably provided with a series of parallelly disposed slots 11 adapted to receive the needle helpers, which are for the purposes of the present invention divided into two groups, alternately disposed, the needle helpers of the first group being designated by reference character 12 and the needle helpers of the second group being designated by reference character 13.

As more clearly shown in Figs. 1, 3 and 4 of the drawing, the needle helpers 12 and 13 are provided with the bed-engaging portions 14' and 14'', respectively, and with the preferably shorter needle-engaging portions 15' and 15'', respectively, the needle-engaging portions 15' and 15'' being spaced from the bed-engaging portions 14' and 14'', respectively, as by means of the respective grooves 16' and 16'', which grooves preferably extend inwardly from the needle ends 17' and 17'', respectively, of the respective helpers 12 and 13.

The reason for preferably making the bed engaging portion 15 of the helper longer than the needle engaging portion 14 is to secure stability and balance during operation. That is, when the helper is moved upwardly

as hereinafter mentioned, the engaging portion 14 becomes, in a sense, an integral part of the needle itself. Therefore, obviously unless the body engaging portion 15 is lengthened, there will be no balance between the portion 14 and needle and the portion 15, which will be detrimental to the smooth and balanced operation of the mechanism as a whole.

10 It will be noted that the helpers 12 and 13 are substantially H-shaped. It may here be stated that the jacquard card-engaging portions of the helpers 12 and 13 have here been designated by reference characters 18' and 18'', respectively. The helpers 12 and 13 may be quite conveniently and economically fabricated by stamping the same, by means of suitably shaped dies, out of sheet steel or like material having the necessary strength and elasticity, after which the stamped needle helpers may be polished or subjected to any other suitable finishing operation.

25 As clearly illustrated in the various figures of the drawing, the jacquard card-engaging portions 18' of the needle helpers 12, comprising one of the two series of needle helpers, are staggered or displaced with respect to the jacquard card-engaging portions 18'' of the remaining needle helpers 13, 30 comprising the alternately disposed series of needle helpers. It will be noted that by means of this arrangement sufficient space is provided for the accurate and certain operation of the needle helpers 12 and 13, 35 which are alternately disposed with respect to each other, within the respective grooves 11 of the auxiliary or other needle bed 10, while at the same time permitting an unusually large number of such needle helpers 40 to be conveniently disposed within a unit of length of the auxiliary or other needle bed 10.

45 This is rendered possible by means of the staggered disposition of the jacquard card-engaging ends 18' and 18'' of the respective needle helpers 12 and 13. This arrangement, of course, requires a new type of jacquard card which, however, is not a part of the present invention, being more fully described and being fully claimed in a 50 co-pending application filed of even date here-with and entitled "Card for jacquard knitting machines". It may be sufficient, however, here to state that the needle-helper engaging elements of this novel form of jacquard card are likewise staggered or displaced with respect to each other and are disposed in separate rows, one row of elements 55 to be adapted to engage the jacquard card-engaging portions 18' of the series of needle helpers 12, and the other row of elements, staggered or displaced with respect to the first row of elements referred to and likewise 60 spaced therefrom, being adapted to engage

the jacquard card-engaging portions 18'' of the remaining series of needle helpers 13.

65 The construction described above is sufficiently clear from the foregoing description. Likewise the manner of assembling 70 and operating the devices described above will be readily apparent to those skilled in the art to which the present invention relates. The foregoing construction enables the remarkably compact assembly of the needle helpers and thus the disposition of an unusually large number of needle helpers within a unit of length of the auxiliary needle bed 10 or the like, thus permitting a very fine and compact jacquard pattern to be knitted 75 into the fabric made by the jacquard knitting machine to which the construction of the present invention is applied. The devices of the present invention are, at the same time, simple in construction, easy and economical 80 to fabricate, easy to apply, and certain, convenient and accurate in operation.

85 It may here be stated, by way of further explanation, that the auxiliary needle helpers of the present invention are also termed in the knitting art in which the same are intended to be employed "needle jacks", and are particularly adapted for use with jacquard knitting machines, the forward end 90 of each needle helper or jack as it slides in its particular groove in the needle bed engaging the rear or butt end of its respective needle, while the rear end of each needle helper or jack as it slides in its appropriate groove in the needle bed is engaged by the 95 jacquard card or passes through a groove or slot in such card, depending on whether the particular needle helper or jack and thus the particular needle associated therewith is intended to be operative or left in inoperative 100 position.

105 What we claim as our invention is:

1. A needle helper comprising a bed-engaging portion and a needle-engaging portion spaced therefrom, said bed-engaging portion extending substantially parallel to but forwardly of said needle-engaging portion.

110 2. A needle helper comprising a bed-engaging portion and a needle-engaging portion spaced therefrom by a cut-out portion 115 extending inwardly from the needle end of the helper, said bed-engaging portion extending substantially parallel to but forwardly of said needle-engaging portion.

120 3. A needle helper comprising a bed-engaging portion and a needle-engaging portion spaced therefrom by a cut-out portion extending inwardly from the needle end of the helper, said bed-engaging portion extending substantially parallel to but forwardly of said needle-engaging portion, together with a rearwardly-extending card-engaging portion.

125 4. A needle helper comprising a bed-en- 130

gaging portion and a needle-engaging portion spaced therefrom, said bed-engaging portion extending substantially parallel to but forwardly of said needle-engaging portion, together with a rearwardly-extending card-engaging portion.

5. A pair of needle helpers each comprising a bed-engaging portion and a needle-engaging portion spaced therefrom, said bed-engaging portion extending substantially parallel to but forwardly of said needle-engaging portion, the card-engaging portions of the respective needle helpers being staggered with respect to each other.

10. A pair of needle helpers each comprising a bed-engaging portion and a needle-engaging portion spaced therefrom by a cut-out portion extending inwardly from the needle end of the helper, said bed-engaging portion extending substantially parallel to but forwardly of said needle-engaging portion, the card-engaging portions of the respective needle helpers being staggered with respect to each other.

15. A pair of needle helpers each comprising a bed-engaging portion and a needle-engaging portion spaced therefrom, said bed-engaging portion extending substantially parallel to but forwardly of said needle-engaging portion, together with a rearwardly-extending card-engaging portion, the card-engaging portions of the respective needle helpers being staggered with respect to each other.

20. A pair of needle helpers each comprising a bed-engaging portion and a needle-engaging portion spaced therefrom by a cut-out portion extending inwardly from the needle end of the helper, said bed-engaging portion extending substantially parallel to but forwardly of said needle-engaging portion, together with a rearwardly-extending card-engaging portion, the card-engaging portions of the respective needle helpers being staggered with respect to each other.

25. A pair of needle helpers each comprising a bed-engaging portion and a needle-engaging portion of different length spaced therefrom by a cut-out portion extending inwardly from the needle end of the helper, together with a rearwardly-extending card-engaging portion, the card-engaging portions of the respective needle helpers being staggered with respect to each other.

30. In testimony whereof, we have signed our names to this specification this 8th day of September, 1924.

SIDNEY WORMS.
JOSEF KELLNER.
